DESIGN FOR A MOTOR DRIVEN BLOWER
FOR CLEANING, DRYING, AND SPRAYING
PURPOSESEdwin W. Vose, Orange, N. J., assignor to Spray
Process Co. Inc., a corporation of New York

Application August 27, 1946, Serial No. 132,897

Term of patent 14 years

(Cl. D62—2)

To all whom it may concern:

Be it known that I, Edwin W. Vose, a citizen of the United States and resident of Orange, in the county of Essex and State of New Jersey, have invented, a new, original, and ornamental Design for Motor Driven Blower for Cleaning, Drying, and Spraying Purposes, of which the following is a specification, reference being had to the accompanying drawings, forming part thereof, in which:

Figure 1 is a plan view of a blower, for cleaning, drying, and spraying purposes, showing my new design;

Figure 2 is a side elevation thereof;

Figure 3 is a left end view showing the inlet of the blower; and

Figure 4 is a right end view showing the exhaust end of the blower.

I claim:

The ornamental design for a motor driven blower for cleaning, drying, and spraying purposes, as shown.

EDWIN W. VOSE.
